[57] CLAIM

[**] Term: 14 Years

The ornamental design for a closure vent arrangement cap, as shown and described.

[21] Appl. No.: 63,387

DESCRIPTION

[22] Filed: Dec. 6, 1996

FIG. 1 is a top perspective view of a closure vent arrangement cap embodying the principles of the present invention, the cap being illustrated with lettering in phantom lines on the top surface thereof, which lettering is not part of the claimed design;

[51] LOC (6) Cl. 09-07

FIG. 2 is a bottom perspective view of the closure vent arrangement cap of FIG. 1;

[52] U.S. Cl. D9/453

FIG. 3 is a top view of the closure vent arrangement cap of FIG. 1;

[58] Field of Search D9/435, 536, 452,

FIG. 4 is a bottom view of the closure vent arrangement cap of FIG. 1; and,

D9/453, 454, 503, 529; 215/200, 217, 230,
307, 310, 316, 328, 329; 220/200, 202,

288

FIG. 5 is a side view of the closure vent arrangement cap of FIG. 1, the opposite side view being a mirror image thereof.
